UNITED STATES PATENT OFFICE.

GEORGE W. THOMPSON, OF PITTSBURGH, PENNSYLVANIA.

PIPE WRENCH.

Application filed December 16, 1926. Serial No. 155,131.

This invention relates to wrenches and more in particular to adjustable pipe-wrenches.

The primary object of this invention is to provide a pipe-wrench having its clamping jaws placed directly at the front, instead of at the side of the wrench, thereby affording better means for reaching pipes located very close to walls or at other places where they cannot be engaged by wrenches having lateral jaws, such as the well known "Stillson"-type of wrenches. Another object of this invention is to provide a wrench having secondary adjusting means which permit of a better engagement of the wrench with a pipe, after the jaws of the former have been adjusted by means of the usual type of regulating worm. A further object of this invention is the provision of a pipe wrench which is simple in construction, efficient, and well adapted for quantity manufacture. Additional features and advantages of this invention will appear from the following description considered in connection with the accompanying drawing, forming a part of this application, and in which:

Fig. 1 is a side elevation of my wrench, when first applied to a pipe, shown in dot and dash lines.

Fig. 2 is a fragmentary side elevation showing the movable jaw of the wrench in final operating position.

Fig. 3 is a perspective view of the handle of the wrench.

Fig. 4 is a perspective view of the movable jaw supporting-plate.

Fig. 5 is a perspective view of the movable jaw-member, with the adjusting-worm.

Reference being had to the drawing, my improved pipe-wrench comprises the operating handle 1 consisting of the body-portion 2 and the holding-portion 3. At the forward end of the body-portion is secured by means of a pin 4 the removable jaw 5. Intermediate said jaw and the holding-portion 3 the handle has a longitudinal slot 6 extending through the whole width of the body-portion.

Hingedly mounted on the pin 7 and rockable within the slot 6 is the movable-jaw supporting-plate 8 upon which is in turn rockably mounted, on the fulcrum-pin 9, the movable jaw-member 10. The latter consists of the two parallel legs 11 suitably spaced to receive therebetween the supporting-plate 8. At the head 12 of the jaw-

member is removably secured by means of the pin 13 the movable-jaw 14, and there is also mounted in the aperture 15 the adjusting-worm 16, rotatable about a screwed-in 60 pin 17. This adjusting-worm engages suitably cut teeth 18 provided on the supporting-plate and disposed concentrically about the fulcrum-pin 9.

Acting upon the inner end of the supporting-plate is the leaf-spring 19 having its stationary end secured to the operating-handle by means of a screw 20. This spring is preferably placed within a recess 21 in the handle, to give it greater protection and 70 keep it from protruding too much out of the handle. The normal tendency of this spring is to cause the supporting-plate to rotate counterclockwise (as seen in the drawing) a certain amount which is limited 75 by the lug 22 on the supporting-plate striking a stop 23 provided within the handle 1. As will be readily understood from the drawing, a counterclockwise rotation of the supporting-plate about the pin 7 will cause 80 the priorly adjusted movable-jaw to exert a certain yielding pressure on the pipe, thereby insuring a better gripping engagement of the pipe by the jaws. The latter are, of course, provided with suitably directed corrugations or teeth 24, adapted to better grip or bite into the periphery of the pipe, thus preventing slipping of the wrench.

When a pipe is to be screwed in or out, the workingman presses with the thumb of 90 one hand on the rear end of the supporting-plate to overcome the pressure of the spring 19, so that said plate will assume the position shown in Fig. 1. He then causes the clamping-jaws to press on the pipe by rotating the adjusting-worm in the proper direction. This done, the thumb-pressure on the supporting-plate is released in order to enable the leaf-spring to act upon said plate, thus adding extra pressure, of a yielding 100 nature, of the jaws on the pipe. The wrench may now be rotated in the proper direction to screw-in or out the pipe without having to contend with any slipping of the wrench around the pipe.

As will be understood, there may be slight changes made in the construction and arrangement of the details of my invention without departing from the field and scope of the same, and I intend to include all such 110 variations, as fall within the scope of the appended claims, in this application in

which the preferred form only of my invention has been disclosed.

I claim:—

1. In a pipe-wrench, a handle having a longitudinal aperture provided therein; a stationary jaw secured at one end of said handle; a supporting-plate hingedly connected to said handle and rockable within said aperture; a movable jaw-member hingedly mounted on said supporting-plate; an adjusting-worm rotatable within said jaw-member there being teeth cut on said supporting-plate adapted to be engaged by said worm for the purpose of moving said jaw-member toward and away from said stationary jaw,
2. In a pipe-wrench, a handle having a longitudinal aperture provided therein; a stationary jaw removably secured at one end of said handle; a supporting-plate hingedly connected to said handle and rockable within said aperture; a movable jaw-member hingedly mounted on said supporting-plate; an adjusting-worm rotatable within said jaw-member; teeth cut on said supporting-plate adapted to be engaged by said worm for the purpose of rotating said jaw-member toward or away from said stationary jaw, and means adapted to normally rotate said jaw-member toward said stationary jaw.
3. In a pipe-wrench, a handle having a longitudinal aperture provided therein; a stationary jaw removably secured at one end of said handle; a supporting-plate hingedly

connected to said handle and rockable within said aperture; a movable jaw-member hingedly mounted on said supporting-plate; an adjusting worm rotatable within said jaw-member; teeth cut on said supporting-plate and concentric to the fulcrum of the jaw-member adapted to be engaged by said worm for the purpose of rotating said jaw-member toward or away from said stationary jaw, and yielding means adapted to normally rotate said jaw-member toward said stationary jaw.

4. In a pipe-wrench, a handle having a longitudinal aperture provided therein; a stationary jaw removably secured at one end of said handle; a supporting-plate hingedly connected to said handle and rockable within said aperture; a movable-jaw member hingedly mounted on said supporting plate, said jaw-member having a pair of legs disposed in spaced parallel relation and adapted to slidably receive therebetween said supporting-plate; an adjusting-worm rotatable within said jaw-member; teeth cut on said supporting-plate and concentric to the fulcrum of the jaw-member adapted to be engaged by said worm for the purpose of rotating said jaw-member toward or away from said stationary jaw, and yielding means adapted to normally rotate said jaw-member toward said stationary jaw.

In testimony whereof I affix my signature.

GEORGE W. THOMPSON.
